Patented June 13, 1972

223,825

INSECT ELECTROCUTING TRAP

Robert D. Kahn, Rockville Centre, N.Y., assignor to
Fedtro, Inc., Rockville Centre, N.Y.

Filed Mar. 15, 1971, Ser. No. 124,618

Term of patent 14 years

Int. Cl. D22—06

U.S. Cl. D22—19

FIG. 1

FIG. 2

FIG. 3

FIG. 4

FIG. 1 is an isometric view showing the top, front and side of the insect electrocuting trap;

FIG. 2 is a top plan view thereof;

FIG. 3 is a front elevational view thereof; and

FIG. 4 is a bottom plan view thereof.

I claim:

The ornamental design for an insect electrocuting trap, as shown.
